UNITED STATES PATENT OFFICE

WILBUR FRANCIS CRAWFORD, OF WACO, TEXAS

SHIPPING JACKET FOR PERISHABLE COMMODITIES

Application filed February 26, 1931. Serial No. 518,540.

This invention relates to shipping jackets of the kind employed to protect ice cream, milk and other perishable commodities against deterioration while being delivered.

- 5 The invention forming the subject of this application will be found to comprise a tubular insulating body in which the inner fabric wall thereof is provided with a series of spaced longitudinal ribs defining longitudinal chambers opening out through the upper end of the tubular body and adapted for the reception of a free flowing refrigerant, the series of chambers being extended entirely about the outer side of the commodity container positioned within the body or jacket so that the refrigerant may have that intimate contact with the container necessary for the effective preservation of the contents of the container.
- 10 The invention will further be found to reside in the means by which the aforesaid internal ribs are defined without materially increasing the cost of manufacture of the jacket or impairing the strength thereof.
- 15 The invention also contemplates a shipping jacket in which the closure thereof is in the nature of a three flap arrangement leaving one side of the jacket free for the expeditious introduction of a commodity container into the jacket and at the same time providing improved insulation and reducing the cost of manufacture of the closure.

- 20 Other objects and advantages will be apparent during the course of the following description.
- 25 Figure 1 is a perspective of a shipping jacket constructed in accordance with this invention.
- 30 Figure 2 is a plan view of the jacket with the closure flaps thereof in closed position.
- 35 Figure 3 is a fragmentary side elevation illustrating the upper portion of the jacket with the flaps thereof in closed position.

- 40 Figure 4 is a fragmentary side elevation illustrating the upper portion of the container, the view being taken at right angles to the illustration in Figure 3 and being partly broken away to illustrate the internal rib arrangement by which there is formed a series of refrigerant receiving chambers ex-

tending entirely about the commodity container.

Figure 5 is a horizontal sectional view taken on line 5—5 of Figure 4.

Figure 6 is a detail perspective illustrating the manner in which the ribs are formed.

In the drawing the numeral 10 generally designates a tubular body of any desired cross section and having the lower portion thereof closed by a bottom or boot 11. Figure 4 illustrates that the body 10 is formed of inner and outer layers 12 and 14, respectively, between which there is a layer of insulating material 16 of any nature such, for example, as horse hair or felt. The layers 12, 14 and 16 are held firmly together at suitably spaced points by rows of stitching 18 that may extend both longitudinally and transversely of the jacket and which, of course, hold the layer of insulating material securely in place.

Referring now to Figures 4 and 5, it is pointed out that the inner layer 12, of a fabric such as canvas, is provided with a series of longitudinally extending inwardly projecting folds or pleats within which lengths of such form giving or reinforcing material as rope are secured to define a plurality of uniformly spaced ribs 20. The folds or pleats by which the ribs 20 are formed are stitched at the points of connection thereof with the inner wall 12 to secure the form giving cores of the ribs in place.

Figure 5 illustrates that the inwardly projecting ribs 20 define intervening longitudinal chambers extending entirely about the container enclosed within the jacket and adapted for the reception of a free flowing refrigerant such as CO₂ by which the perishable contents of the jacket enclosed container are preserved during shipment.

Attention is now invited to Figures 1 and 4 illustrating that the form giving cores of the ribs 20 terminate short of the upper end or top of the tubular body 10 and therefore, in effect, provide an enlarged entrance opening at the mouth of the jacket to facilitate the entrance of a commodity container into the jacket. It is clearly illustrated in Figure 1 that the folds by which the ribs 20 are formed extend up to the extreme top of the

jacket and are secured by transverse stitching to such top. That is to say, the upper portions of the pleats by which the ribs 20 are formed have the side surfaces thereof secured flatly against the inner side wall of the jacket by stitching or other suitable means to aid in the formation of a gradually restricted entrance opening for the container of ice cream or the like, and at the same time to form 10 gradually restricted openings for the entrance of the refrigerant into the chambers therefor.

The closure arrangement for the mouth of the jacket embodies a single inner flap 30 of 15 substantially rectangular formation and a pair of outer flaps 32 adapted to overly the inner flap and overlap each other in the manner suggested in Figure 3.

The flaps 30 and 32 may be of the same 20 material as the body 10 of the jacket and may be secured to the upper ends of the side walls of the jacket or constitute continuations of such side walls.

Figure 4 illustrates that the single inner 25 rectangular flap 30 is of an area sufficient to extend entirely across the mouth of the jacket and is provided on the under side thereof with a depending plug or pad 36 having dimensions causing it to fit snugly within the mouth 30 of the jacket. In this connection, it is pointed out that the cores of the ribs 20 terminate below the upper end of the jacket not only to provide an enlarged entrance opening for the reception of a can of ice cream or the like 35 but to allow of the entry of the depending pad 36 into the mouth of the jacket. As might otherwise be expressed, the edge portions of the single inner flap 30 are rabbeted to define a depending portion 36 and marginal flanges, the latter being adapted to engage 40 the upper end of the body 10.

The inner flap 30 is provided with a plurality of fastening straps 40 adapted for connection with buckles 42 secured to the sides 45 of the body 10.

As shown in Figure 3, when the straps 40 are fastened in place, the otherwise free end portion of the inner flap 30 will be caused to bend over the adjacent end of the body 10 50 and have substantially fluid tight contact therewith.

The outer flaps 32 are adapted to be brought into the overlapping relation suggested in Figure 3 and are provided with 55 straps 46 and buckles 48 by which the same may be secured in place. When the straps 46 are fastened, the side edges of the inner flap 30 are pressed against the adjacent upper ends of the body 10 to provide substantially 60 fluid tight seals at these points.

In use, a can of ice cream or the like is placed snugly within the body 10 and to provide additional protection against deterioration 65 of the contents of the container during shipment, a quantity of free flowing refriger-

erant may be introduced into the refrigerant receiving chambers defined by the ribs 20. It is noted that the refrigerant when thus placed within the container has intimate and generous contact with the side walls of the can 70 for the full length thereof. Now, it is a simple matter to secure the flaps 30 and 32 in place and during shipment the protection provided by the insulation of the body will be augmented materially by the refrigerant contained within the jacket making it possible 75 to ship perishable commodities long distances without deterioration.

It might be added that, as illustrated in 80 Figure 1, the upper end of one side wall is entirely free and it is over this free end that a commodity container may be passed to introduce the same into the container through the gradually restricted entrance opening as 85 previously described.

Having thus described the invention, what is claimed is:

1. In a jacket for shipping perishable commodities, a tubular insulating body adapted 90 for the snug reception of a commodity container and having an inner fabric wall provided with a series of spaced pleats, pliable cores within said pleats and terminating short of the upper ends of said body leaving the upper portions of said pleats unoccupied 95 to form a gradually restricted entrance opening to the body, the unoccupied portions of said pleats being secured flatly to the upper portion of the body, and a closure having a depending plug adapted to be snugly received within the enlarged entrance opening 100 to said body and bearing against the unoccupied portions of said pleats.

2. In a jacket for shipping perishable commodities, a tubular insulating body adapted 105 for the snug reception of a commodity container and having an inner fabric wall provided with a plurality of inwardly extending spaced longitudinal pleats, form giving cores within said pleats to define inwardly projecting ribs adapted for engagement with the wall of the container placed within the body and forming chambers adapted for the reception of a free flowing refrigerant, said cores terminating short of the upper ends of 110 said pleats to provide an enlarged entrance opening for a commodity container, and a closure having a portion adapted to be snugly received within said entrance opening to said body and bearing against the upper ends of 115 said pleats.

3. In a jacket for shipping perishable commodities, a tubular insulating body having an inner fabric wall formed with a series of spaced pleats and cores within said pleats to 125 define internal ribs and intervening chambers, the chambers being adapted for the reception of a free flowing refrigerant.

4. In a jacket for shipping perishable commodities, a tubular insulating body having 130

an inner fabric wall formed with a series of spaced pleats defining internal ribs and intervening chambers, the chambers being adapted for the reception of a free flowing
5 refrigerant, means for flatly securing the upper portions of said pleats to the upper portion of said body to provide an enlarged entrance opening to the body, and a closure having a portion adapted to be snugly received within said enlarged entrance opening and bearing against the upper portions of
10 said pleats.

In testimony whereof I affix my signature.
WILBUR FRANCIS CRAWFORD.
